R. F. WHERLAND.
ELECTRICALLY-HEATED APPARATUS.
APPLICATION FILED DEC. 13, 1920.

1,423,380.

Patented July 18, 1922.

R. F. Wherland INVENTOR

BY Victor J. Evans
ATTORNEY

Paul M. Hunt

WITNESS:

UNITED STATES PATENT OFFICE.

ROBERT F. WHERLAND, OF STANLEY, NORTH DAKOTA.

ELECTRICALLY-HEATED APPARATUS.

1,423,380.

Specification of Letters Patent. Patented July 18, 1922.

Application filed December 13, 1920. Serial No. 430,225.

To all whom it may concern:

Be it known that I, ROBERT F. WHERLAND, a citizen of the United States of America, residing at Stanley, in the county of Mountrail 5 and State of North Dakota, have invented new and useful Improvements in Electrically-Heated Apparatus, of which the following is a specification.

This invention relates to an electrically 10 heated apparatus, and the object is to provide a device of the type indicated, which shall be especially adapted for use in a battery service station, for heating battery compound.

15 A further object is to provide a device of the character indicated which shall include a receptacle provided with a main interior chamber for the compound, a pouring tube connected therewith, said tube enclosing a 20 heat conducting element, having connection with a duct passing through the main chamber, and an electrically heated device enclosed within said duct.

A still further object is to provide, 25 broadly, an electrically heated device, for the purpose indicated, in which the material to be heated shall be placed under, or subjected to, a high temperature, not only within the main chamber of the apparatus, but 30 also in the discharge spout, whereby the required fluid condition is maintained as long as possible.

With the foregoing and other objects in view, the invention consists in the novel construction, combination, and arrangement of 35 elements hereinafter described and claimed.

In the drawings, Figure 1 is a top plan view of the device, and Figure 2 is a view in vertical section and side elevation.

40 In carrying out my invention, I provide a receptacle of any suitable form and capacity, the form shown in the drawing being adapted for the purpose indicated. The main portion of the receptacle is designated 45 10 and a cover 12 is provided therefor, and likewise a handle 13.

A tubular element 14 connects with the inner chamber of the receptacle and has connection with a discharge spout 15. The 50 latter may be supported by a handle 16. A layer of asbestos 17 is shown as being located in the lower portion of the chamber 10, and serves as a non-conducting element. Within the tubular element 14 is a duct 20, extend-

ing to a point above the element 14 and having connection at its lower end with the duct 21 which passes through the main chamber and preferably in an inclined direction. Heated air passes through a duct or housing 21 and thence upwardly through the 60 duct 20, so that the compound within the element 14 is maintained at a temperature approaching the temperature in the main receptacle. An electric heating unit includes a member 24 receiving current through connections 25 and 26. A cord for connection with a source of current supply is designated 27, the usual plug 28 effecting the connection with the terminals of the resistance coil. 70

In actual use the device has proved to be highly efficient, and the fact that the compound is poured from a point below the surface is of importance since the impurities collecting on the surface are not poured off, 75 as with the use of a ladle.

While the duct 20 maintains the heat to the required degree, it is so proportioned that the heat of the compound will not be excessive when being discharged. 80

What I claim is:

1. A device of the class described, comprising a receptacle, a duct extending transversely therethrough, a discharge spout, a tube extending through said spout and having connection with the aforesaid duct, and an electrically heated element within said duct. 85

2. A device of the class described comprising a receptacle, a discharge spout therefor, an electric heating unit within the receptacle, and means for conducting heated air from said unit through the discharge spout. 90

3. A device of the class described comprising a receptacle, a cover therefor, a tubular member connected with one side of the receptacle at a point below the top thereof, a housing within the receptacle, extending transversely thereof and having one end open, the opposite end projecting into the 100 tubular member, an air duct extending from said housing through the tubular member, a discharge element projecting from said tubular member, and a handle connected with the discharge element. 105

In testimony whereof I affix my signature.

ROBERT F. WHERLAND.
